METHODS OF MAKING HEAT EXCHANGERS

This invention relates to methods of making heat exchangers for example for use in the coolant systems of internal combustion engines.

The invention provides a method of making a heat exchanger of the kind comprising a stack of sheet metal pressings in face to face relation, adjacent pairs of pressings providing between them alternately channels for flow of coolant and spaces for the flow of air, which method comprises joining pairs of pressings which provide between them spaces for flow of air by cold welding and then joining the thus formed pairs of cold welding to provide the channels for flow of coolant.

The cold welding of each pair of pressings and of the pairs of pressings may be carried out in a number of cold welding operations at adjacent locations.

The cold welding operations may be carried out at overlapping locations.

A fin or fins may be secured to the pressings in each air space.

Prior to the cold welding of the pressings to form pairs, a fin of wave or zig-zag form may be welded at alternate crests to the side of each pressing which bounds an air space.

The crests of the fins may be cold welded to the pressing.

The fins may be located on the pressings so that crests on the fins of adjacent pressings abut one another.

In the case where each pressing has two spaced depressions having openings in the bottom thereof, a channel connecting the two depressions and a peripheral flange extending along either side of the channel and around the depressions, pairs of pressings may first be assembled with the spaced depressions of one pressing in engagement with the spaced depressions of another pressing, the engaging depressions are cold welded together and the resulting pairs of pressings are assembled with their flanges in engagement and then the flanges are cold welded together.

The following is a description of a specific embodiment of a radiator for a motor vehicle constructed in accordance with the invention reference being made to the accompanying diagrammatic drawings in which:

FIG. 1 is a side view of part of one of the pressings which makes up the radiator;

FIG. 2 shows the pressing with finning applied to one side;

FIG. 3 is a side view of two pressings and a tool for securing the pressings together;

FIG. 4 is an enlarged view of part of the tool for securing the pressings together;

FIG. 5 is a plan view of the assembly shown in FIG. 3;

FIG. 6 is a side view of two of the assemblies shown in FIG. 3 and a tool for securing them together;

FIG. 7 shows a pattern of welds which may be used, using a tool such as that of FIG. 6; and

FIG. 8 shows a further pattern of welds which may be used.

Referring firstly to FIG. 1 a pressing indicated by the reference numeral 10 formed from aluminium sheet is shown having an outer peripheral flange 11 and a depression 12 adjacent one end of the pressing with an opening 13 in the bottom of the depression. The pressing is formed with a similar depression at its other

end and a channel 14 extends along the pressing between the depressions.

Referring now to FIG. 2 of the drawings finning formed by bending a thin strip 16 of aluminium into wave formation is cold welded along the spaced crests on one side of the strip to the outside of the channel 14 of the sheet 10 between the depressions 12.

As shown in FIG. 3 of the drawings two of the pressings 10 are offered up together with the spaced depressions 12 on one of the sheets in engagement with the spaced depressions 12 on the other sheets. The engaging parts of the depressions around the openings 13 are then cold welded together by a tool comprising upper and lower dies 17 and 18. The die 18, as shown in FIG. 4, is formed with a projecting ring 19 on its upper surface and the die 17 is formed with a similar projecting ring 20 on its lower surface. The lower die 18 is introduced through the open side of the depression 12 in the lower pressing and the upper die 17 is introduced through the open end of the depression 12 in the upper pressing and the dies are brought together with sufficient force to cold weld the engaged parts of the depressions trapped between the ring 19 and the ring 20 together. The engaging depressions at both ends of the pressings are welded together in this manner. The bottoms of the channels 14 of the resulting assembly are spaced apart to permit flow of air between them.

The finning formed by the bent strip 16 is located on the two pressings so that the crests on one of the strips which are spaced from the pressing abut the crests of the other strip which are spaced from the pressing to which the other strip is secured.

Two of the assemblies thus formed are then offered up together with their flanges 11 (see FIG. 5) in face to face relationship and the flanges 11 are cold welded together by the tool illustrated in FIG. 6 of the drawings which comprises upper and lower dies 21 and 22 which have oppositely projecting rims 23, 24. A length of the abutting flanges to be cold welded together is introduced between the rims on the dies 21, 22 as shown in FIG. 6 and a load is applied to the upper die 21 sufficient to effect cold welding of the flanges. A further length of the flanges is introduced between the dies and is cold welded and this is repeated until the entire peripheries of the flanges have been cold welded. Preferably the flanges are welded together at overlapping locations. In a modified method, illustrated in FIG. 7, the flanges 11 are first welded along the full lines 30 and then along the broken lines 31 to form a continuous weld. Alternatively the end parts of the flanges may be welded as shown in FIG. 8 using a modified form of the tool shown in FIG. 6 which forms U-shaped weld lines as indicated at 32, the remaining parts of the flanges being welded by a tool of the type shown in FIG. 6 along the straight lines 33. If desired two modified tools may be used to weld the opposite end parts of the flanges simultaneously. This helps to avoid distortion.

Further assemblies are then secured to the other peripheral flanges of the double assembly thus formed until a stack of sufficient units has been formed.

The communicating depressions 12 at either end of the stack form header tanks to which supply and return conduits are connected. The channels 14 form commu-

nicating passages for flow of coolant between the two headers and cooling air passes between the spaced bottoms of the channels.

We claim:

1. A method of making a heat exchanger of the kind comprising a stack of sheet aluminum or aluminum alloy pressings in face to face relation, each pressing having two spaced depressions each provided with an opening in the bottom thereof, a channel connecting the depressions and a peripheral flange, which method comprises the steps of:
  - a. firstly locating fins of wave form having spaced crests on each pressing on the outside of the channel thereof with certain crests of the waves abutting the channel and the remaining crests spaced from the channel;
  - b. secondly internally supporting the channel;
  - c. thirdly applying pressure to those crests abutting the channel to cold weld the crests to the channel and at the same time to form grooves in the channel which receive said crests;
  - d. fourthly assembling pairs of the pressings together with the depressions of adjacent pressings in engagement with one another and said remaining crests of the fins of the pressings in engagement with one another;
  - e. fifthly cold welding said depressions together;
  - f. sixthly assembling the resulting pairs in face to face

relation with the peripheral flange of one pressing abutting the peripheral flange of another pressing; and

- g. finally cold welding the peripheral flanges together.

2. A method as claimed in claim 1 wherein the cold welding of each pair of depressions and of each pair of abutting peripheral flanges is carried out in a series of cold welding operations at adjacent locations.

10 3. A method as claimed in claim 1 wherein the cold welding of each pair of depressions and of each pair of peripheral flanges is carried out in a series of cold welding operations at overlapping locations.

4. A method as claimed in claim 1 wherein the fins 15 are located on the pressings so that crests on the fins of adjacent pressings of each pair abut one another.

5. A method as claimed in claim 1 wherein step (e) of claim 1 is performed in two cold welding operations comprising cold welding portions of the flanges 20 together and then cold welding the remaining portions of the flanges together to form a continuous weld.

25 6. A method as claimed in claim 1 wherein step (e) of claim 1 is performed in two cold welding operations comprising cold welding the end parts of the flanges together to form U-shaped weld lines and cold welding the remaining parts of the flanges together to form a continuous weld.
